UNITED STATES PATENT OFFICE.

EDWARD BRUNHOFF, OF WYOMING, OHIO, ASSIGNOR TO THE BRUNHOFF MANUFACTURING COMPANY, OF CINCINNATI, OHIO, A CORPORATION OF OHIO.

DISPLAY LID.

Application filed June 9, 1927. Serial No. 197,730.

My invention relates to improvements in display lids. One of its objects is to provide an improved display lid adapted to be more readily constructed and assembled. Another object is to provide an improved strip of a design adapted to form an improved display lid. Another object is to provide an improved arrangement and assembly of frame members and transparent panel adapted to be more conveniently assembled, and while holding the transparent panel in place facilitating removal and replacement of broken panels. My invention also comprises certain details of form and arrangement, and combination of components, all of which will be fully set forth in the description of the accompanying drawings, in which:

Fig. 1 is a plan of a strip of sheet metal adapted to be employed as a portion of the metal frame of my improved display lid.

Fig. 2 is a perspective view of my improved lid in inverted position.

Fig. 3 is an enlarged detail of a portion of my improved lid, partly in vertical section.

Fig. 4 is an enlarged sectional detail taken on line 4—4 of Fig. 2.

Fig. 5 is an enlarged sectional detail taken on line 5—5 of Fig. 2.

The accompanying drawings illustrate the preferred embodiment of my invention in which 15 represents a strip of sheet metal from which the front and sides of a sheet metal frame are to be formed by bending the sheet metal stamping shown in plan in Fig. 1 along the dotted lines of Fig. 1 to form three sides of a sheet metal frame of channel shaped cross-section. A sheet metal frame member 16 is designed to be attached near its opposite ends to the respective rear ends of one web or side of the frame member 15. A panel 17 of glass or similar transparent material is designed to be slipped from the rear into the channeled frame 15, after the frame members 15 and 16 have been assembled and united.

It is desirable to construct the frame members 15 from stock which has been previously surface finished, for instance electro-plated or lacquered. It is also desirable to finish the surface of the members 16, as for instance by electro-plating or lacquering the same, and also by applying advertising matter or ornamental designs to the members 16,

which can be done to advantage before the members 15 and 16 are united.

In order to provide for uniting the members 15 and 16 after they have been separately formed and surface finished the members 15 have sections of their lower webs 22 cut away at 24 at the ends thereof, and their upper webs 25 are perforated at 26 opposite the cut-away portions 24. Thus when the members 15 are bent to channel shaped cross-section, the portions of the upper web 25 carrying the perforations 26 come opposite and above the cut-away portions 24, and thereby provide for the introduction of hollow rivets 28 through the perforations 26 and through corresponding perforations 29 through the member 16, and also provide for the introduction of a riveting punch or riveting tool to the under face of the rivets to clinch the rivets so as to firmly unite the rear ends of the frame member 15 to the frame member 16 near opposite ends thereof without liability to mar, injure or corrode the surface finished frame members during the operation of uniting them.

At the localities where the frame member is to be bent to form the corners of the frame, the webs 22 and 25 are notched at 30 and 31 in Fig. 1, and said notches are so proportioned that when bent to substantially the form shown in Figs. 2 and 4 the notch edges 34 of the side sections of member 15 will telescope with and underlap the notch edges 35 and thereby centrally guide and prevent the front edge 36 of the panel 17 from coming into contact with the edges 35 or with the edges 40 or 41, in such manner as to interfere with introducing the panel 17 into the channel of member 15 across the front of the frame, which would otherwise be liable to occur in the assembly of a large percentage of the frames, thereby requiring extra time in assembling or introducing the panels and liability of injury to the frame or to the panel, due to attempting to force the panel into place against resistance encountered when the front edge of the panel reaches the front section of frame member 15. In this manner I am enabled to insure introduction of the several panels into their frames without material resistance, and without injury or loss of time.

After the panels have been introduced into position in the frames, the rear ends 38

of the middle sections 37 and those uncut away portions of the ends of the lower webs are bent inwardly in rear of the rear corners of the panel 17 as shown in Figs. 2 5 and 5 to thereby prevent the panel being retracted from the frame or becoming accidentally displaced or detached. In the event that the panel should become broken, the bent-in sections 37 may be bent outwardly 10 sufficiently to allow the broken panel to be removed and a new panel inserted, after which the sections 38 are bent inwardly again to hold the panel in place. The inwardly turned ends 42 and 43 of the frame 15 member 16 enable the edges of the lid of an original package to be engaged in the channels 44 so that the original lid and display lid move in unison.

The article herein shown and described is 20 capable of considerable modification within the scope of the claims without departing from the spirit of my invention.

What I claim is:

1. In a display lid in combination with a 25 transparent panel, a sheet metal frame member of channel shaped cross-section to embrace the front and opposite sides of said panel with the ends of the upper and lower webs of the side sections of said frame in- 30 terposed between the faces of the panel and the ends of the upper and lower webs of the front section of said frame at the front corners of said panel, and a rear sheet metal frame member extending across the rear of 35 said panel and above said panel and attached to the rear ends of the upper web of said channel shaped frame member, said rear frame member being provided with members adapted to operatively connect 40 said display lid to the lid of an original package.

2. In a display lid in combination with a transparent panel, a sheet metal frame mem-

ber of channel shaped cross-section to embrace the front and opposite sides of said 45 panel and with the rear ends of the upper web of said frame member perforated and the rear ends of the lower web of said frame member cut away opposite the perforated portion of the rear ends of the upper web, 50 and a rear frame member of angular cross-section having one web thereof perforated near opposite ends thereof to register with the perforations in the rear ends of said 55 channeled frame member and adapted to be attached to the rear ends of the upper web of said channeled frame member by rivets, said rear frame member being provided with members adapted to operatively connect said display lid to the lid of an original package 60 to move in unison therewith.

3. In a display lid in combination with a transparent panel, a sheet metal frame member of channel shaped cross-section to embrace the front and opposite sides of said 65 panel and with the rear ends of the upper web of said frame member perforated and the rear ends of the lower web of said frame member cut away opposite the perforated portion of the rear ends of the upper web 70 and a rear frame member extending across the rear of said panel and above said panel and attached to the rear ends of the upper web of said channel shaped frame member, said rear frame member being provided with members adapted to operatively connect said 75 display lid to the lid of an original package, and the rear ends of said channel shaped frame member being provided with bent over portions to engage the rear edge of said panel to retain said panel in place relative to the frame.

In testimony whereof I have affixed my signature.

EDWARD BRUNHOFF.
